UNITED STATES PATENT OFFICE.

HENRIK HILLBOM, OF WALLINGFORD, CONNECTICUT, ASSIGNOR TO R. WALLACE & SONS MFG. CO., OF WALLINGFORD, CONNECTICUT, A CORPORATION.

DESIGN FOR A METAL BORDER.

SPECIFICATION forming part of Design No. 36,244, dated March 10, 1903.

Application filed January 24, 1903. Serial No. 140,447. Term of patent 7 years.

To all whom it may concern:

Be it known that I, HENRIK HILLBOM, of Wallingford, in the county of New Haven and State of Connecticut, have invented and produced a new, original, and ornamental Design for a Metal Border; and I do hereby declare the following, when taken in connection with the accompanying drawing and the letters of reference marked thereon, to be a full, clear, and exact description of the same, and which said drawing constitutes part of this specification and represents a top or plan view of an ornamental metal border embodying my design.

This invention relates to an ornamental design for a metal border; and it consists in the configuration as shown in the accompanying illustration.

As herein shown, the border consists of two

reversely-turned scrolls A B, surmounted by 20 two reversely-curved scrolls C D, and these scrolls are connected by a long double-ended scroll E with scrolls F, G, H, and I, similar to but slightly less elaborate than the scrolls A, B, C, and D.

Having fully described my invention, what I claim as new, and desire to secure by Letters Patent, is—

The ornamental design for a metal border, as herein shown and described.

In testimony whereof I have signed this specification in the presence of two subscribing witnesses.

HENRIK HILLBOM.

Witnesses:
